BY *John F. Kerr*

ATTORNEY.

UNITED STATES PATENT OFFICE.

CHARLES R. SMITH, OF PATERSON, NEW JERSEY.

UPRIGHT BOILER.

SPECIFICATION forming part of Letters Patent No. 738,853, dated September 15, 1903.

Application filed May 7, 1903. Serial No. 155,989. (No model.)

To all whom it may concern:

Be it known that I, CHARLES R. SMITH, a citizen of the United States, residing at Paterson, in the county of Passaic and State of New Jersey, have invented certain new and useful Improvements in Upright Boilers, of which the following is a specification, reference being had therein to the accompanying drawings.

10 My invention relates to upright boilers; and the objects of the invention are, first, to provide a fire-box and fire-box shell that will give an increased fire-grate area; second, to provide in a boiler a barrel of such a character and construction as to admit of a man walking around inside thereof for the purpose of cleaning and obviate the objections to the boilers in vogue, in which access to the parts for cleaning purposes is either difficult or impossible, and, third, to increase the efficiency of boilers by means for the admission of air at any or all parts of the walls surrounding the ash-pit and form a central-draft upright boiler. I attain these objects 15 by the construction illustrated in the accompanying drawings, in which—

Figure 1 is a view, partly in front elevation and partly in vertical section on the line *y* in Fig. 2, of a boiler embodying my invention; and Fig. 2 is a cross-sectional view through boiler and base on the line *o* in Fig. 1.

Similar letters refer to similar parts in both views.

The boiler is set on a cast-iron or brick 35 ring *A*, forming the ash-pit *A'*, provided with door *a*, and a series of openings *a'* with doors *a'*, surrounding the ash-pit, the number and size of the same depending upon the circumference and other dimensions of the pit.

40 The fire-box *B* is conical-shaped, having a sloping wall *C* and the crown-sheet *c* slightly arched, which gives an increased area for the fire-grate *b*. Doors *b'* around the fire-box may be provided in numbers according to the 45 size of the boiler.

The lower barrel portion *D* of the boiler-shell is slightly conical-shaped and is much greater in diameter than the upper barrel portion *G*. It is secured or braced to the 50 fire-box wall *C* by bolts *d* or other suitable means and is provided with the hand-holes *d'*.

The barrel portion *E* is above the fire-box and is of such a diameter as to permit a man to enter the manhole *e* and walk around in

the space *e'* between the barrel *E* and the 55 boiler-flues *c'* on the fire-box shell or on the bolts or braces *d* for the purpose of cleaning the boiler. The conical or sloping barrel portion *F* connects the portion *E* to the portion *G*, which latter portion is of lesser diameter and is provided with the usual top or smoke-chamber *H*.

In operation aside from the facility with which the boiler may be cleaned an efficiency hitherto unattained results from the equalization of draft procured by means of the series of radially-arranged doors or dampers surrounding the ash-pit. The air admitted from many parts of the circumference tends to the center, the combustion is uniform and 70 the whole fuel is subject to the same action.

With this description of my invention, what I claim, and desire to secure by Letters Patent, is—

1. In a boiler, the combination with the 75 flues and the fire-box, of a barrel or shell comprising an upper portion, a lower portion above the fire-box of an increased diameter having a manhole, and a sloping or conical portion connecting the upper and lower portion forming a space between the flues the fire-box and the barrel, substantially as set forth.

2. In a boiler, an ash-pit having radially-arranged doors or dampers, in combination 85 with a conical fire-box having an arched crown-sheet, a conical fire-box shell and a cylindrical barrel, comprising an upper portion, a lower portion having a manhole, and a conical section connecting the upper and 90 lower portions and forming a space between the barrel and the flues and fire-box, substantially as set forth.

3. In an upright boiler, a fire-box having a curved crown-sheet and sloping walls increasing in diameter toward the bottom, in combination with a grate, and an ash-pit having radially-arranged doors in the walls thereof, and a boiler-shell varying in diameter at different points, forming an annular 100 chamber between the shell and the boiler-flues, substantially as set forth.

In testimony whereof I affix my signature in presence of two witnesses.

CHARLES R. SMITH.
